UNITED STATES PATENT OFFICE.

WILLIAM H. BURNS, OF ST. LOUIS, MISSOURI.

PROPELLING AND STEERING VESSELS.

SPECIFICATION forming part of Letters Patent No. 338,162, dated March 16, 1886.

Application filed April 6, 1885. Serial No. 161,264. (No model.)

To all whom it may concern:

Be it known that I, WILLIAM H. BURNS, of the city of St. Louis, in the State of Missouri, have invented a certain new and useful Improvement in Propelling and Steering Apparatuses, of which the following is a full, clear, and exact description, reference being had to the accompanying drawings, forming part of this specification.

10 Figure 1 is a side view of the improvement when the screw-shaft is in line with the keel of the vessel. Fig. 2 shows the screw in end view, its shaft being at right angles with the keel. Fig. 3 is a detail horizontal section at 15 3 3, Fig. 2, showing the propeller-screw and its supporting-frame in top view.

A is the stern portion of a vessel, and B the keel.

C and D are brackets in which the tiller-shaft T has bearing.

20 F is a tiller by which the tiller-shaft may be turned; but I do not confine myself to this means of turning said shaft, as any device may be used for this purpose. Upon the tiller-shaft is fixed a frame, G, in which the shaft H of the propeller-screw I has bearing. Upon the shaft H is a bevel cog-wheel, J, which 25 engages a bevel cog-wheel, K, upon a vertical shaft, L, which has bearing at the ends in the frame G, and whose axis is in line with the axis of the tiller-shaft, so that the turning of the tiller-shaft does not affect the position of the shaft L. Upon the shaft L is a bevel cog-wheel, M, which engages with a bevel-wheel, 30 N, upon the shaft O, which is rotated by the steam-engine.

35 It will be readily seen that the propeller may have continuous rotation while the tiller-shaft is turned upon its bearings, and that 40 when the propeller-shaft is inclined to either side the propeller will operate as a rudder to

steer the boat when the boat or vessel is passing through the water, and it will be seen that by means of the propeller, when in the position shown in Figs. 2 and 3, the boat or vessel 45 may be turned around without having any endwise movement in the water.

An inclined position of the propeller is shown in dotted lines in Fig. 3.

I have shown the frame G as little more 50 than a simple frame, the bars having no great width in the plane of the frame; but it may be preferred to extend the frame so as to form a rudder, as shown by dotted lines in Figs. 1 and 3.

55 I am aware that it is not broadly new to secure a screw-propeller within the rudder-frame and connect it to the operating-shaft through gearing, and do not claim such, broadly, as my invention.

60 I claim—

In a steering-propeller, the combination of the brackets C and D, the oscillating frame G, stepped into said brackets, the tiller-shaft E, connected to the frame G, the short vertical shaft I, journaled at both ends in the frame G concentrically with its axis of oscillation, the propeller-shaft H, journaled at its ends in said frame, the propeller-screw secured to said propeller-shaft at a point intermediate of its 65 journals, the beveled cog-wheel J on said propeller-shaft, the operating-shaft O, having the beveled cog-wheel N, and the beveled gear secured to the vertical shaft L and connecting the operating-shaft with the propeller-shaft, 70 all constructed and arranged to operate substantially as set forth.

75 WILLIAM H. BURNS.
